SNARE DRUM THROW-OFF OR SIMILAR ARTICLE

Robert N. Grauso, Bayside, and John J. Morena, Levittown, N.Y., assignors to C. F. Martin & Co., Nazareth, Pa.

Filed Apr. 30, 1971, Ser. No. 139,308

Term of patent 14 years

Int. Cl. D17—04

U.S. Cl. D56—1 E

FIG. 1

FIG. 2

FIG. 3

FIG. 4

FIG. 5

FIG. 1 is a left side elevational view of a snare drum throw-off or similar article showing our new design, the opposite side being substantially a mirror image thereof;
FIG. 2 is a front elevational view;

FIG. 3 is a rear elevational view;

FIG. 4 is a top plan view; and

FIG. 5 is a bottom plan view thereof.

We claim:

The ornamental design for a snare drum throw-off or similar article, substantially as shown and described.
